(57) **CLAIM**

The ornamental design for a container for packaging products, as shown and described.

DESCRIPTION

FIG. 1 is a perspective view of a container according to a first embodiment of our ornamental design, showing the front, bottom and right side of the packaging container; FIG. 2 is a front view of the container shown in FIG. 1, wherein a back view is mirror image of the front view; FIG. 3 is left side view of the container shown in FIG. 1, wherein the right side view is a mirror image of the left side view;

FIG. 4 is top down view of the container shown in FIG. 1, wherein the bottom up is a mirror image of the top down view;

FIG. 5 is a perspective view of the container shown in FIG. 1, wherein dotted lines in the transparent or translucent center portion of the container indicate exemplary products vacuum wrapped by the container;

FIG. 6 is a perspective view of a container according to a second embodiment of our ornamental design, showing the front, bottom and right side of the packaging container; FIG. 7 is a front view of the container shown in FIG. 6, wherein a back view is mirror image of the front view; FIG. 8 is left side view of the container shown in FIG. 6, wherein the right side view is a mirror image of the left side view;

FIG. 9 is top down view of the container shown in FIG. 6, wherein the bottom up is a mirror image of the top down view;

FIG. 10 is a perspective view of the container shown in FIG. 6, wherein dotted lines in the transparent or translucent center portion of the container indicate exemplary products vacuum wrapped by the container;

FIG. 11 is a perspective view of a container according to a third embodiment of our ornamental design, showing the front, bottom and right side of the packaging container; FIG. 12 is a front view of the container shown in FIG. 11, wherein a back view is mirror image of the front view;

(Continued)

FIG. 13 is left side view of the container shown in FIG. 11, wherein the right side view is a mirror image of the left side view;

FIG. 14 is top down view of the container shown in FIG. 11, wherein the bottom up is a mirror image of the top down view;

FIG. 15 is a perspective view of the container shown in FIG. 11, wherein dotted lines in the transparent or translucent center portion of the container indicate exemplary products vacuum wrapped by the container;

FIG. 16 is a perspective view of a container according to a fourth embodiment of our ornamental design, showing the front, bottom and right side of the packaging container;

FIG. 17 is a front view of the container shown in FIG. 16, wherein a back view is mirror image of the front view;

FIG. 18 is side view of the container shown in FIG. 16, wherein the side, top and bottom views are the same as or mirror images of the view shown in FIG. 18; and,

FIG. 19 is a perspective view of the container shown in FIG. 16, wherein dotted lines in the transparent or translucent center portion of the container indicate exemplary products vacuum wrapped by the container.

In the drawings, the broken lines are for the purpose of illustrating environment only and form no part of the claimed design.
